UNITED STATES PATENT OFFICE.

GEORGE W. PRICE, OF BALTIMORE, MARYLAND, ASSIGNOR TO BERNARD N. BAKER, OF SAME PLACE.

ROTARY STEAM-ENGINE.

SPECIFICATION forming part of Letters Patent No. 299,260, dated May 27, 1884.

Application filed November 26, 1883. (No model.)

To all whom it may concern:

Be it known that I, GEORGE W. PRICE, of the city of Baltimore and State of Maryland, have invented a new and useful Improvement 5 in Rotary Steam-Engines, as well as in the method of packing the parts thereof to make them steam-tight, of which the following is a full and clear description.

In the drawings, Figure 1 is a sectional view 10 of the cylinder, showing steam and exhaust ports and reversing attachments, also the packing arrangement for the shaft, the abutments, and top view of the piston. Fig. 2 is an isometric view of the hub, the abutments on their 15 concentric shaft, and the piston. Fig. 3 is an isometric view of the hub and shaft, showing the pistons and packing of the hub. Figs. 4 and 5 are views of the interior faces of the abutments, showing the inclines which serve 20 as guides to propel the pistons from side to side. Fig. 6 is a face view of the piston. Fig. 7 is an interior view of the piston with the face-plate removed, showing the packing device. Fig. 8 is a vertical section of the piston 25 cut through the line $x x$, and by a plane perpendicular to the face of the piston. Fig. 9 is a side elevation of the hub. Fig. 10 is a plan view of the hub. Fig. 11 is a section of the hub. Fig. 12 is an interior view of the packing-rings which surround the periphery of the 30 hub.

A, Fig. 1, represents a central shaft passing through the packing-boxes, and abutments B and B', to which shaft is secured the hub C. 35 B and B' are the abutments. They are located within the cylinder and placed on either side of the hub, in the position shown in Fig. 2. The shaft A is intended to revolve freely in the journal of these abutments, which are held 40 in place by the lugs I and I', which are inserted into the slots formed in the cylinder-heads for this purpose. The abutments are formed as shown in Figs. 4 and 5. The one to the left is marked B in the drawings, and that to the right is marked B'. They are constructed circular in form. The outer faces are planes. The inner surfaces are formed in two parts—an upper or raised surface and a lower or de-

pressed one—divided by a diameter, and connected together by an inclined plane, through 50 which the steam and exhaust ports are shown in Figs. 4 and 5, and marked thereon E and F. The ports, as shown in the figures, exhibit one form in which they may be made. Another, and, perhaps, a preferable, way for the 55 steam to enter and escape is shown in Fig. 1, in which figure the same E and E' represent the steam-ports, and F and F' represent the exhaust-ports. The steam-ports, it will be seen, are thus arranged on the opposite sides 60 of the cylinder and diametrically opposite to each other, and the exhaust-ports are placed on the sides of the cylinder opposite to the steam-ports. The inner surfaces of the abutments B and B', formed as above described, 65 constitute two surfaces on each—one raised and the other depressed. The raised or higher parts are marked in the drawings (see Fig. 2) 70 a', and the lower or depressed parts are marked a. When placed in position, as shown in Fig. 70 2, the raised parts of each are opposite the depressed parts of the other. The plane surfaces of the sides of the hub, together with the abutments thus constructed, on their sides next to the hub, form steam-spaces, which are diametrically opposite to each other, one on each 75 side of the hub, marked in the drawings d and d'. The two inclined planes b and b', which connect the upper and lower surfaces of the abutments, act as guides to the sliding plates 80 or pistons, and direct their movement from side to side, as required.

C is the hub, which may be cast upon the shaft or otherwise secured thereto, and is slotted radially in two places diametrically opposite to each other.

D and D' represent the pistons, of which there are two, (see Fig. 3,) which are placed within these slots in the hub, and when so placed are intended to slide from side to side 90 therein. In practice more than two pistons can be arranged in one machine, if desired. In Fig. 2 one piston is shown which has just passed from the steam-space d, and has crossed over the steam-space d', the left side of this 95 piston passed up the steam-space d until it

came in contact with the inclined plane *b*, by which it was propelled and guided to the other side.

H is an annular cylinder provided with the 5 stuffing-ring *J*.

K is a ring shown in section in Fig. 1, preferably cast upon the outer side of the abutments *B* and *B'*. Its outer diameter is approximately that of the inner diameter of the packing-ring *J*, within which it enters.

L is a packing-ring also, and is secured to the top of the ring *K* by bolts or otherwise. The packing-ring *J* is threaded on its outer circumference, which screws into a thread 15 upon the interior of the circular opening in the cylinder-head, and bears upon the plane outer surfaces of the abutments *B* and *B'*.

Fig. 6 of the drawings is a plan view of the piston, upon which (the figures 1 1 1, &c.,) are 20 the countersunk heads of the bolts for holding the face-plates of the piston together. By removing one of the face-plates, the interior packing arrangement is seen, as shown in Fig. 7. This packing arrangement is constructed 25 as follows: 1 1 1, &c., are the bolts, the heads of which are shown and marked by the same figures as in Fig. 6. 4 4 are irregular-shaped pieces of metal, which, together with the wedge-shaped or triangular pieces 2 2, when 30 put together, form a quadrilateral of the size of the piston. The slots 3 3, cut in the plates 4 4, are intended to allow an outward and inward movement of these plates. 5 is a spring, shown in the drawings in the shape of a wagon- 35 spring, and is placed so as to exert its force on the bases of the two triangular pieces 2 2. It will be seen that by forcing these triangular pieces outwardly, the pieces 4 4 are pressed against the sides of the abutments laterally, 40 against the inner circumferential surface of the cylinder, and against the shaft, thus packing the piston and preventing leakage of the steam.

Fig. 8 is a section of the piston cut through 45 the lines *x x* by a plane perpendicular to the face. 6 6 are the face-plates of the piston, and 7 is the packing. 8 8 are rings cast on the interior of one of the face-plates, through which the bolts 1 1 pass, and which are made high 50 enough to prevent the plates being screwed so tight together as to prevent the packing from working.

Figs. 9, 10, 11, and 12 are intended to illustrate the method of packing the hub to prevent 55 leakage of steam between it and the interior circumferential surface of the cylinder. The hub *C* is turned down around its entire circumference on each side, forming two circular grooves, separated by the central projection of the hub, which is marked on drawings, Fig. 11, with the letter *e*. At the point where these circular grooves unite with the openings in the hub in which the pistons are inserted the hub is cut out, as shown at *f* in 60 Fig. 9. These cut-out spaces are intended to receive the ends of the packing-rings, which

are turned down and formed to fit therein, as shown at *M*, Fig. 12. The packing-rings marked *R* and *R'* occupy the circular grooves turned out in the hub. These rings are in 70 two pieces, one piece of which occupies one of the grooves in the hub, and, running around to the other side, meets the other. The two ends, at their junction, form diagonal parallel lines. These lines are shown at *S S'* in Figs. 75 10 and 12.

O O, Fig. 9, are notches cut in the hub. They are located just under the packing-rings. Their object is to allow the steam to exert its force against the inner part of the rings and 80 press them against the interior of the cylinder. While the packing-rings are thus forced outwardly, the part of the ring turned down at *M* and inserted in the slots *f* keep the rings in 85 place while revolving with the hub, and automatically pack the hub and cylinder and prevent leakage of steam. In order to prevent the escape of steam in the direction of the cylinder-heads, and at the same time take up the wear of the parts, the packing-ring *J* is screwed 90 down against the abutments *B* and *B'* as the parts wear; and the space between the interior of the ring *K* and the shaft *A* is duly supplied with suitable packing, which is adjusted by means of the packing-ring *L*, and its bolts 95 running into the rings *K*.

The operation of the device is as follows: Steam is allowed to enter through the steam-ports *E* and *E'*. Passing into the steam-spaces *d* and *d'*, it strikes the pistons *D* and *D'*, revolving the hub and forcing the pistons from the steam-ports *E* and *E'* to the exhaust-ports *F* and *F'*. When the pistons reach the inclined planes *b* and *b'*, they are forced over to the opposite sides, and the steam which has propelled them is exhausted through the exhaust-ports *F* and *F'*. The steam entering behind the pistons through the steam-ports strikes against the pistons, which have changed sides, propelling them again until they have passed the exhaust-ports, and are forced back by the inclined planes to the sides at which the operation was begun, thus automatically, and by successive impulses, producing continuous revolution of the hub and shaft. The steam-ports *E* and *E'* are so located that the sliding pistons *D* and *D'* may pass them before the pistons have been pushed so far to the other side as to encounter a resistance or back action of the steam against them.

The engine may be easily reversed by means of the valve marked *V* in the drawings, Fig. 1, as will be seen. By pulling upon the valve-stem *I* the valve will close the port *E* and open the inlet *F*, which in turn will become the 125 steam-inlet and *E* the exhaust-outlet. This valve-stem may be packed by means of the stuffing-box arrangement shown at *w*.

Having thus described my invention, what I claim as new, and desire to secure by Letters 130 Patent, is—

1. In a rotary steam-engine, the abutments

B and B', provided with the ring K, in combination with the packing-ring L, provided with means for adjusting said ring, substantially as described, and for the purposes set forth.

2. In a rotary steam-engine, the sliding piston D, operated as set forth, formed of two plates bolted together, in combination with an interior packing device, substantially as described.

3. In a rotary steam-engine, the sliding piston D, containing the internal packing device, consisting of the parts 4 4 4 4, the wedges 2 2, the slots 3 3 3 3, and the spring 5, inclosed within the piston-plates and secured together, substantially as described.

4. In a rotary steam-engine, the piston D,

provided with the internal packing, and means to prevent the outer plates from bearing upon the packing and preventing its proper action, substantially as described.

5. In a rotary steam-engine, the hub c, having exterior circumferential grooves, and the slots f, in combination with the packing rings, formed as shown, and arranged upon the hub, substantially as described.

6. In a rotary steam-engine, the hub c, provided with sockets O, in combination with the packing-rings R and R', substantially as described, and for the purposes set forth.

GEORGE W. PRICE.
